United States Patent Office.

GEORGE D. WILCOX, OF PROVIDENCE, RHODE ISLAND.

Letters Patent No. 77,429, dated April 28, 1868.

IMPROVEMENT IN MUCILAGE-BRUSHES.

The Schedule referred to in these Letters Patent and making part of the same.

TO ALL WHOM IT MAY CONCERN:

Be it known that I, GEORGE D. WILCOX, of the city and county of Providence, in the State of Rhode Island, have invented a new and useful Instrument for Spreading Mucilage or other adhesive gum or paste compound; and I do hereby declare that the following specification, taken in connection with the drawing making a part of the same, is a full, clear, and exact description thereof.

The article is fully represented in the drawing in perspective.

All persons who have occasion to make use of the ordinary mucilage-bottle and brush, have experienced the inconvenience which results from the stiffening of the bristles of the brush from the accumulation of mucilage upon them.

As the mucilage dries upon the bristles, they become much enlarged in size, and spread apart from each other, so as to become of little better service than a stick of the same size.

My improvement consists in substituting, in place of the bristles commonly employed, a flap of flexible material, as, for example, gutta percha or India rubber.

In the drawing, A is the ordinary handle appropriate for such brushes, and B the well-known cap for the bottle. C is a flap, which may be made of gutta percha, India rubber, whalebone, or other material possessing flexibility, and capable of being made in the form shown, from a single piece, but not having the capacity to absorb the mucilage or adhesive mixture.

The flap may be secured in a holder, D, of metal, in an obvious way. The advantages which the instrument possesses are, that it takes up, by adhesion to its surface, all the mucilage required, without becoming overcharged by absorption.

The quantity of mucilage to be spread upon the paper to be pasted can be more nicely regulated, and it can be more easily applied to the paper at the points where it is wanted by this instrument than by the brush in common use.

Besides, too, whenever the flap becomes stiffened by the drying of the mucilage upon its surface, it can be readily put into as good condition as before by washing.

I am aware that a dampening-brush of India rubber, covered by an absorbent of cloth, has been before used. I do not claim, therefore, broadly, a flexible flap in one piece, in place of bristles, where the same is made of a material which is a non-absorbent, or practically so.

What I claim as my invention, and desire to secure by Letters Patent, is—

The improved instrument for spreading mucilage or adhesive compositions, substantially as herein described.

GEORGE D. WILCOX.
